UNITED STATES PATENT OFFICE.

WILLIAM E. CARLSON, OF CONCORD, NEW HAMPSHIRE, ASSIGNOR TO
WILLIAM B. DURGIN COMPANY, OF CONCORD, NEW HAMPSHIRE.

DESIGN FOR A HANDLE FOR SPOONS, FORKS, OR SIMILAR ARTICLES.

SPECIFICATION forming part of Design No. 35,877, dated April 22, 1902.

Application filed January 27, 1902. Serial No. 91,524. Term of patent 7 years.

To all whom it may concern:

Be it known that I, WILLIAM E. CARLSON, a citizen of the United States, residing at Concord, in the county of Merrimack and State of New Hampshire, have invented and produced a new and original Design for Handles for Forks, Spoons, or Similar Articles; and I do hereby declare the following to be a full, clear, and exact description of the same, reference being had to the accompanying drawing, forming a part thereof.

This invention relates to a new and original design for a handle for forks, spoons, and similar articles, and it is represented in the accompanying drawing, wherein the design is shown in elevation, a bonbon-spoon bowl being shown in dotted lines attached thereto and the conventional tines of a fork.

The design consists, essentially, in the representation of a cluster of "cat-tails," their stems being collected to form the shank of the handle, the same being represented as being sheathed in the leaves of the plant, the heads protruding beyond and constituting the end of the handle. Around the stem is entwined a vine.

The essential feature of the design is a handle shaped to represent a cluster of cat-tails, the stems of which are collected and constitute the shank portion, the heads being slightly spread apart and constituting the outer end of the handle. 30

While the design is intended as a handle for forks, spoons, and other similar articles, it is to be understood that the term "similar articles" is here used to designate such other articles to which the handle may be attached, and in this connection the dotted lines represented are employed to illustrate the application to different articles. 35 40

Having thus described the invention, what is claimed as new, and desired to be secured by Letters Patent, is—

The design for a handle for forks, spoons and similar articles, substantially as shown 45 and described.

In testimony whereof I affix my signature in presence of two witnesses.

WILLIAM E. CARLSON.
